POWER MOWER RIDING ATTACHMENT

Ellsworth F. Brewer, Milwaukee, Wis., assignor to E. F. Brewer Company, a corporation of Wisconsin

Application July 11, 1955, Serial No. 36,888

Term of patent 14 years

(Cl. D40—1)

FIG. 1

FIG. 3

Fig. 1 is a side elevational view of a power mower riding attachment showing my new design;

Fig. 2 is a top view of the power mower riding attachment; and

Fig. 3 is a front view of the power mower riding attachment.

The broken line portion of the drawing disclosure is depicted for illustrative purposes only.

I claim:

The ornamental design for a power mower riding attachment, substantially as shown and described.
